W. W. EVANS

FLUE CLEANER

Filed June 5, 1922

William W. Evans
INVENTOR

BY *M. Thomas*

ATTORNEY

UNITED STATES PATENT OFFICE.

WILLIAM W. EVANS, OF SALT LAKE CITY, UTAH.

FLUE CLEANER.

Application filed June 5, 1922. Serial No. 565,970.

To all whom it may concern:

Be it known that I, WILLIAM W. EVANS, a citizen of the United States, residing at Salt Lake City, in the county of Salt Lake 5 and State of Utah, have invented certain new and useful Improvements in Flue Cleaners, of which the following is a specification.

My invention relates to tools for cleaning flues of boilers and has for its object to provide a device that is simple in construction, 10 easy to operate and one whereby soot and other foreign matter may be thoroughly removed from the flues of the boiler.

The invention further contemplates the provision of a flue cleaner in which the possibility of the same becoming jammed in the flue during the cleaning operation is greatly diminished.

These objects and others which will be apparent I accomplish with the device shown in the accompanying drawings in which similar letters and numerals of reference indicate like parts throughout the several views and as described in the specification 25 forming a part of this application and pointed out in the appended claims.

In the drawings Figure 1 is a longitudinal section illustrating my flue cleaning device and the arrangement of the parts with respect to each other. Figure 2 is a plan view of one of the cleaning blades. Figure 3 is a plan view of one of the breaker blades.

My invention comprises the breaker blades and cleaning blades, each of which are used 35 in pairs and staggered in relation to each other in the circumferential direction of the device and between each pair of cleaning blades or each pair of breaker blades, the spacing sleeves are interposed and all of the 40 breaker blades, cleaning blades and sleeves are operatively held in relation to each other on the bolt or shaft of my device. In cleaning flues it is sometimes advantageous to remove the cleaning blades and use only the 45 breaker blades, any number of which may be provided and all used in staggered relation to each other, forming a spiral in their general assembly, and the completed device, whether carrying the breaker blades or the 50 cleaning blades, is to be run through the flues. The outer edge of both the breaker blades and the cleaning blades are cut as a segment of a circle corresponding with the inner face of the flue. The blades are of thin 55 spring steel, and in forcing the device through the flues the segment-cut-ends of the

blades come in contact with the inner surface of the flue and scrape and break from the inner surface of the flue any accumulation of soot, rust or other matter. The staggered relation of the different blades is in order that the blades may operate similar to the teeth of a screw when the device is moved longitudinally back and forth in the flue. The various elements of the device 60 are arranged on a bolt 1 having a square head and externally threaded on the opposite end. A segment of the bolt is cut away as at 11 to form a flat bearing surface and the breaker blades and cleaning blades have 65 a centrally disposed hole, circular in general aspect, but the circle is not completed in one portion thereof to conform to the flat surface of the bolt 1. I provide a convex guide ring B adjacent the head of the bolt 1 for 70 the purpose of directing and guiding the device into the flue. Preferably I next place on the said bolt 1 one of the spacer sleeves 2, and then next in order one of the breaker 75 blades 3 and adjacent that another breaker blade in which the flattened part of the circle is changed or modified so that the second breaker blade 3 will assume a different position as to the bolt and other breaker 80 blade, giving the staggered effect. I then place on said bolt another one of the spacer sleeves 2, and next in order, another pair of breaker blades 3, likewise staggered in relation to each other and to the first pair of breaker blades by the position of the flattened portion of the hole 5 therein. Preferably I then use a spacer sleeve 2', somewhat longer than the spacer sleeves 2 and loosely carried on said spacer sleeve 2' is the cleaning washer 6 of smaller diameter than 85 the breaker blades 3 and, which is a flat washer having a central opening therein somewhat larger than the diameter of the spacer sleeve 2' in order that said washer may be 90 free to move laterally as to the bolt 1 and spacer sleeve 2'. When in use said washer is the sweeping means for carrying out the soot and other matter that the breaker blades and cleaning blades break loose. Next in 95 order I prefer to use another pair of staggered breaker blades, and between said breaker blades and another pair of breaker blades I provide another of the spacer sleeves 2, and on the opposite side of the last pair of breaker blades another spacer sleeve, and 100 screwed on said bolt and against the last mentioned spacer sleeve is the collar 8. I 105 110

then provide a concavo-convex guard 9 internally threaded and screwed on the threads of the bolt 1. The guard 9 extends purposely beyond the end of the said bolt 1, providing an internally threaded hole shown at 10, within which I screw the handle of my device.

In the operation of my device, the narrowed ends of the breaker blades, which are 10 the first element introduced into the flue of sufficient diametrical length to scrape the flue, will break down and remove from the wall of the flue the soot which will be carried out by the washer 6. The cleaning 15 blades and the sweeping rings will clean the remaining portion of the soot and sweep it from the flue, performing the further process of cleaning. In the operation of running my device through a flue, the 20 staggered position of the breaker blades and cleaning blades will insure the entire inner surface to be scraped and cleaned by passing the device one or more times through the flue. By reason of having the opening in 25 the washer 6 larger than the sleeve 2' on which the washer is carried during the operation of my device, the washer will assume a position and engage the inner surface of the flue, thus cleaning out any dislodged soot, and my device will not only loosen the soot but will also sweep it from the flue after it is loosened.

After using the breaker blades with the annular washer 6 to break down and remove some of the soot, I preferably reassemble the cleaner by changing the breaker 35 blades and using the cleaner blades 4 to thoroughly clean the interior of the flue. The cleaner blades 4 are assembled and 40 spaced in pairs by the spacer sleeves 2, in the same manner as the breaker blades 3. As will be obvious if it is so desired, the 45 two forms of blades 3 and 4 may be associated and assembled by using breaker blades adjacent the collar B; then a sleeve spacer 2; then a pair of cleaning blades with the sleeve washer 2' and washer carried thereon; then another pair of cleaning blades

spaced from the final or end pair of breaker blades held in place by the collar 8 and 50 guide member 9.

To prolong the life of my cleaner, I provide extra breaker blades and cleaning blades to replace dull or defective ones when desired.

Having described my invention and its use I desire to secure by Letters Patent and claim:—

1. In a device of the class described the combination of a headed bolt with a flat 60 surface on one side of the shank thereof; a guide collar adjacent the head of the bolt; breaker blades having a circular opening in each with a flattened portion corresponding to the flattened face of the bolt; and staggered in relation to each other; spacing sleeves carried on said bolt to space other breaker blades likewise staggered in relation to each other and carried on said bolt; a sweeping washer loosely carried medially on 70 said bolt and of smaller diameter than the breaker blades; a sweeping collar of concavo-convex form carried on said bolt; with an internally threaded opening therein to receive the thread of a handle.

2. A flue cleaner comprising a headed bolt with a flat surface on one side of the shank thereof; a guide collar adjacent the head of the bolt; blades having a circular opening in each with a flattened portion corresponding to the flattened portion of the bolt, and staggered in relation to each other; spacing sleeves carried on said bolt to space other blades likewise staggered in relation to each other and carried on said bolt; a 80 sweeping washer loosely carried medially on said bolt and of smaller diameter than the breaker blades; and a sweeping collar guard internally threaded to be screwed on said bolt to hold the said blades in place and to 85 provide a threaded opening for the handle of the device.

In testimony whereof I have affixed my signature.

WILLIAM W. EVANS.
